UNITED STATES PATENT OFFICE.

ALPHONSUS L. DRUM, OF HIGHLAND PARK, ILLINOIS.

SUBWAY CONSTRUCTION.

1,069,931.

Specification of Letters Patent. Patented Aug. 12, 1913.

Application filed April 1, 1913. Serial No. 758,100.

To all whom it may concern:

Be it known that I, ALPHONSUS L. DRUM, a citizen of the United States, residing at Highland Park, in the county of Lake and 5 State of Illinois, have invented certain new and useful Improvements in Subway Construction, of which the following is a full, clear, and exact description, such as will enable others skilled in the art to which it applies 10 to make and use the same.

This invention relates to subway construction.

One of the objects thereof is to provide a practical construction for subways having a 15 capacity for handling extreme passenger traffic without congestion.

Another object is to provide a subway station of simple form in which the passenger traffic is readily handled without inconvenience 20 to the passengers and in which the space for the construction is economically used.

Other objects will be in part obvious and in part pointed out hereinafter.

25 The invention accordingly consists in the features of construction, combinations of elements and arrangement of parts which will be exemplified in the construction hereinafter set forth, and the scope of the application of which will be indicated in the following claims.

In the accompanying drawings, in which is shown one of various possible embodiments of this invention, Figure 1 is a plan 35 of a construction for subways; Fig. 2 is a plan of the station construction of the subway shown in Fig. 1; Fig. 3 is a cross-section along the line X—X of Fig. 1; Fig. 4 is a cross-section along the line Y—Y of 40 Fig. 2.

Similar reference characters refer to similar parts throughout the various views.

Referring now to Fig. 1 of the drawings, there are shown a plurality of through 45 tracks 1, 1 and 2, 2, the former being preferably used for local train traffic and the latter tracks for express trains. In this figure there are shown, in somewhat diagrammatic form, two consecutive stations, 50 3 and 4, traversed by these tracks. These stations may be considered representative of a large number through which these tracks pass, and if desired local stations communicating with the outer tracks only may be interposed in the system.

At each of the stations shown there are

provided three island platforms, 5, 6 and 7, serving for the loading and unloading of the trains and positioned at about the floor level of cars on the tracks. The station is 60 provided at a higher level, as best indicated in the sectional views, with longitudinal platforms or walks, 8 and 9, substantially registering with the sidewalks of the street above and extending over the outer tracks 65 1. These platforms are connected by the transverse galleries 10 substantially at opposite ends of the station and a wider transverse platform, or promenade, 11. From the latter platform suitable stairways 12 70 lead to the station platforms and are protected by rails, gates or other devices, as indicated at 13, to insure prepayment of fare. These stairways, if desired, may be of the escalator type and similar stairways 75 lead from the island platforms to the upper level, as indicated at 14 and 15. These various points of communication with the several island platforms are so spaced in position and so ample in capacity as to insure 80 the even flow of currents of passengers without a tendency to congestion and the proper distribution upon the several platforms.

The several tracks 1 and 2 extend between the various stations at a substantially constant depth below the street level and thus provide an ample air space and it is to be noted that the platforms 8 and 9 extend continuously from station to station. One advantage due to this construction lies in the 85 convenience to passengers whereby upon leaving the trains they may walk substantially to their destination without inconvenience due to encountering the traffic of busy streets or inclement weather conditions. 90 Another and even more important advantage, however, lies in the following feature: By the construction of station 4, which is substantially identical with station 3, it will be seen that the passenger traffic is readily 95 guided between the mezzanine level and the station platform level in either direction. From the above level, however, to the street there would, unless special means were provided, be a tendency to congestion which 100 would be even aggravated by the large passenger capacity of these stations. There are here provided, however, from the longitudinal platforms 8 and 9, as well as lateral extensions 16 and 17, at the various street corners, a large number of exits 18 whereby the 105 passengers may be received from the street 110

- level or discharged thereto at an extremely large number of points. Due to the fact that the passengers are permitted, by the construction above described to walk to their precise destination along the route from the nearest station and even to a point offset from the route by the lateral extensions, the passengers are not discharged through constricted passages in a highly localized area but are evenly distributed along the entire route and adjacent sections. In like manner, the entering passengers are drawn from an equally large area through an equally ample number of inlets.
- 15 It is to be noted that if desired the longitudinal or through platforms 8 and 9 may be provided throughout a portion of their width with moving sidewalks, diagrammatically indicated at 19. It will also be seen that by these relatively elevated longitudinal platforms at each station, the necessity for platforms outside the local tracks is done away with, thus permitting the tracks to be properly spread and spaced at each station without reaching the building line of the street. Between stations the tracks may be converged into closer relation, as indicated, if desired. It is also to be noted that the lateral extensions 17 of the longitudinal platforms may be carried a block or more beneath the sidewalks of cross streets, as 20, to another subway, a station of which is diagrammatically indicated at 21, thus providing a covered medium of transfer from a station of one subway to that of another. If desired, suitable gates, as 22, may be provided in this extension whereby fares may be collected from pedestrians passing from one subway to the other.
- 40 The method of use of the above construction has been in large part explained. It may be noted that the passengers may enter the system at any one of the various stairways 18 and walk to the nearest station, either by the extensions 16 or through platforms 8 and 9, as may be necessary. At the station, entrance is gained to the island platforms as by the stairs or escalators 12. The discharged passengers are accommodated by the stairways 14 and 15 and pass through the upper platforms to their destinations.
- 45 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.
- 50 Having described my invention, what I claim as new and desire to secure by Letters Patent is:
- 65 1. In a subway construction, in combination, a plurality of tracks, a plurality of

stations, longitudinal platforms at each station respectively coacting with said tracks and positioned at substantially the floor level of cars thereon, and a covered longitudinal platform at a level above the level of cars at said stations and below the street level and extending from one to another of said stations.

2. In a subway construction, in combination, a plurality of tracks, a plurality of stations, longitudinal platforms at each station respectively coacting with said tracks and positioned at substantially the floor level of cars thereon, and a pair of covered longitudinal platforms spaced one from another, 75 positioned at a level above the level of cars at said stations and below the street level and extending from one to another of said stations.

3. In a subway construction, in combination, a plurality of tracks, a plurality of stations, longitudinal platforms at each station respectively coacting with said tracks and positioned at substantially the floor level of cars thereon, a longitudinal platform at a 80 level above the level of cars at said stations and extending from one to another thereof, and cross-platforms extending from said last platform transversely above the tracks.

4. In a subway construction, in combination, a plurality of tracks, a plurality of stations, longitudinal platforms at each station respectively coacting with said tracks and positioned at substantially the floor level of cars thereon, a covered longitudinal platform at a level above that of cars at said stations and below the street level and extending from one to another of said stations and lateral extensions substantially at the level of said last platform and directed away 95 from said tracks.

5. In a subway construction, in combination, a plurality of tracks, a plurality of stations, longitudinal platforms at each station respectively coacting with said tracks and positioned at substantially the floor level of cars thereon, a longitudinal platform at a level above that of cars at said stations and extending from one to another of said stations, means connecting said second platform with said first platforms, and means connecting the street with said second platform.

6. In subway construction, in combination, a plurality of tracks, a plurality of stations, a plurality of longitudinal platforms at each station positioned to receive passengers directly from cars upon said tracks, a plurality of transverse platforms extending across the tracks above the train level 120 and a longitudinal platform connecting said transverse platforms.

7. In subway constructions, in combination, a plurality of tracks, a plurality of stations, a plurality of longitudinal platforms 125

- at each station positioned to receive passengers directly from cars upon said tracks, a plurality of transverse platforms extending across the tracks at one of said stations 5 above the train level, and a pair of spaced longitudinal platforms connecting said transverse platforms and substantially at the same level therewith. 8. In subway construction, in combination, a plurality of tracks, a plurality of stations, a plurality of longitudinal platforms at each station positioned to receive passengers directly from cars upon said tracks, a plurality of transverse platforms extending 15 across the tracks at one of said stations above the train level, a pair of longitudinal platforms each of which extends over one of said tracks and means leading from said last platforms to said first platforms. 20 9. In subway construction, in combination, a plurality of tracks, a plurality of stations, a plurality of longitudinal platforms at each station positioned to receive passengers directly from cars upon said tracks, a plurality of transverse platforms extending 25 across the tracks at one of said stations above the train level, a pair of longitudinal platforms extending throughout the station at a level above that of cars at the station 30 and lateral extensions from said last platforms directed away from said tracks. 10. In subway construction, in combination, four through tracks, a plurality of stations each comprising three island platforms respectively positioned between adjacent tracks, a pair of through platforms positioned at a level above the train level 35 and extending from station to station spaced one from another, means adapted to permit passengers to pass from said through platforms to said island platforms, and means adapted to permit passengers to pass from said through platforms to the street level. 40 11. In subway construction, in combination, four through tracks, a plurality of stations each comprising three island platforms respectively positioned between adjacent tracks, a pair of through platforms positioned at a level above the train level and extending from station to station spaced one from another, means adapted to permit passengers to pass from said through platforms to said island platforms, means adapted to permit passengers to pass from said through platforms to the street level, and lateral extensions from said through platforms directed away from said tracks. 45 50 55 12. In subway construction, in combination, a subway comprising a plurality of tracks, a plurality of stations, longitudinal platforms at each station respectively coacting with said tracks and positioned at substantially the floor level of cars thereon, a covered longitudinal platform at a level above the level of cars at said stations and 60 below the street level and extending from one to another of said stations, a second subway spaced from said first subway and a passage below the street level extending from a station upon said first subway to a station upon 65 said second subway. 70

In testimony whereof I affix my signature, in the presence of two witnesses.

ALPHONSUS L. DRUM.
